TENSION SCREEN

Jacob M. Gwynne, Coral Gables, Fla.

Application October 22, 1951, Serial No. 252,446

2 Claims. (Cl. 160—328)

1

This invention relates to window screens, and particularly to screens of the "tension" type in which no rigid frame is employed for the screen, which is suspended between the head and sill of a window opening and kept taut by being placed under tension.

A general object of the invention is to provide a tension screen of superior design and construction, relatively small cost, and one which is capable of being securely fastened in place in such manner that the risk of inadvertent loosening or displacement is substantially eliminated.

Another object of the invention is the provision for adjustment for wide tolerances in the plumb and level and height of the window opening by varying the height of the angle screw supports at both top and bottom of the screen.

Another object of the invention is the provision of a window screen of the character described, including special cam-type locking devices for placing the screen under tension easily, each said device comprising fixed locking means secured to the sill of the window and a cooperating locking cam pivoted on a rigid member disposed along the lower edge of the screen, for engagement with the fixed locking means. The fixed locking means or angle screw is adjustable in height to take care of variance in length of screen or window, but is fixed as a locking device as soon as the number of turns inserted in sill for good tension has been determined by test.

The cam surface of the said pivoted cam comprises an entering portion having a geometrically decreasing rate of rise until it reaches the locking portion where the increase in rise is zero, whereby when the said locking portion is engaged with the fixed locking means, there is no turning moment in either direction exerted on the pivoted cam, or in other words, the forces acting between the cam and the locking means are exactly vertical. Inasmuch as this geometrical decrease in rate of rise on the cam is inversely proportional to the build-up of tension in the screen as it is being locked, the design not only provides easy locking and unlocking with a minimum of friction, but provides a stable lock that will not vibrate loose. The latter condition is due to the additional fact that the point of zero rate of rise on the cam is also (when the cam is in locking position only) the only point of tangency or contact between the cam and the locking device that is also on the vertical line of tension between the top screen screw support, the bottom (or locking) angle screw support, and the pivot point of the cam.

Other and further objects, features and ad-

2

vantages will be apparent from the description which follows, read in connection with the accompanying drawings in which

Figure 1 is an elevational view, looking from the inside of the building, of a window frame provided with the screen according to the present invention;

Figure 2 is a transverse vertical section on line 2—2 of Figure 1;

Figure 3 is a perspective view, on an enlarged scale, of the left-hand portion of the screen shown in Figure 1; and

Figure 4 is an enlarged detail view illustrating the curvature of the cam surface.

In order to facilitate an understanding of the invention, reference is made to the embodiment thereof shown in the accompanying drawings and detailed description language is employed. It will nevertheless be understood that no limitation of the invention is thereby intended and that various changes and alterations are contemplated such as would ordinarily occur to one skilled in the art to which the invention relates.

Referring now to the drawings, the window frame illustrated in Figure 1 is of conventional construction comprising a sill 10, jambs 11 and 12, and head 13. Each of the jambs 11 and 12 and the head 13 are provided with inwardly extending sash stops 14 against the outer side of which the screen is adapted to be seated. The sash stop 14 is the outer member defining the guide or groove in which the outer and upper sash of a double-hung window is slidable. For purposes of clarity, no sash is shown in the drawings.

The upper surface of the sill 10, as best seen in Figure 2, is rabbeted to provide a vertical shoulder 15 against which the lower edge of the screen is adapted to seat, that portion of the upper sill surface lying outwardly thereof and identified by the numeral 16 being preferably slightly inclined downwardly and outwardly to facilitate drainage of atmospheric moisture therefrom. The construction thus far described is conventional, and not a part of the invention.

It may be fabricated of wood, metal, or other suitable material. The screen of the present invention comprises generally the sheet 20 of square or rectangular mesh material, such as steel, bronze or aluminum screen wire, or square or rectangular mesh screen material fabricated of plastic filaments, such material being in common use today. The sheet 20 is clamped between head and sill channels 21 and 22, respectively, which are shown in section in Figure 2 and in perspective in Figure 3. The head channel 21 is

formed with a groove 23 adjacent its lower edge, and into which the upper edge of the sheet 20 is tightly jammed by means of a spline 24. The sill channel 22 is similarly formed with a groove 25 adjacent its upper edge in which the lower edge of the sheet 20 is fastened by means of a spline 26. The channels 21 and 22 and splines 24 and 26 may be made of any suitable material, being fabricated preferably of light non-corrosive material such as aluminum or sheet bronze.

The head channel 21 is provided with spaced apertures 27 for engaging similarly spaced angle screws 28 anchored in the sash stop 14 of head 13 of the window frame, the transverse portions of the angle screws 28 being slightly inclined downwardly and inwardly, as best seen in Figure 2, to insure that the screen, when pulled downwardly, is thus biased inwardly to fit firmly against the sash stops 14. Preferably, the head channel 21 is also provided with one or more handles 29 to facilitate installation and handling of the screen.

The sill channel 22 is preferably provided with an adjustable extension member 30 of narrow U-section to slidably embrace the lower edge of the sill channel 22, and which may be provided with an outwardly or inwardly, or both, and downwardly extending lip 31 which not only provides reinforcement against deformation of the sill channel, thus insuring accurate seating of the same against the shoulder 15, but also provides some measure of protection against entry of atmospheric moisture under the lower end of the extension 30. The sliding engagement between the extension member 30 and the sill channel 22 permits accommodation of the latter to inequalities in the vertical width of the shoulder 15, from its one end to the other but, more importantly, permits adjustment of the overall length of the screen to accommodate minor variations, from standard, in the height of the window opening.

Toward either end of the sill channel 22, and preferably located directly beneath the supporting hooks 28, are secured cam members 35, mounted on pivots 36. The latter may conveniently comprise headed bolts or rivets 37 tightly secured to the sill channel 22 by means of nuts 38 and 39, a washer 40 being interposed between each cam 35 and its associated nut 38.

The construction of the cams is best seen in Figures 3 and 4. Each cam preferably consists of a sheet metal stamping, or the like, and is formed with a turned-over handle portion 41 for ease in manipulation. The nose or operative portion of the cam, is provided with an upper or camming surface 43 which engages hooks 42 anchored in the sill 10 at points directly beneath the hooks 28.

The character of the profile of the camming surface 43 is a particular feature of the present invention, and comprises an entering portion having a geometrically decreasing rate of rise indicated at 43a until it reaches the locking portion of the cam where the increase in rise is zero as indicated at 43b. The curve 43 is an arc of a circle whose center lies on the vertical line joining the top and bottom support hooks 28 and 42, respectively, and the cam pivot, the distance of the center of such arc above the pivot point of the cam being chosen so as to give the cam the proper amount of "travel" to apply the desired degree of tension to the screen. Since the radius of said arc is different from (longer than) the pivot radius of the cam, there will be only one

cam position in which the cam surface will contact the hook 42 at a point which is exactly on the aforesaid vertical line, such position being the locking position defined above, and preferably the cam is so formed that when it occupies the defined locking position, the handle portion 41 is exactly horizontal.

When the cam is in locking position, the forces acting between the cam and hook will be exactly vertical, with no resulting torque acting on the cam and tending to cause its inadvertent disengagement. The geometrically decreasing rate of rise insures the absence of humps or other abrupt changes in curvature of the cam surface, facilitating the locking and unlocking of the screen while, at the same time, the danger of its vibrating loose is eliminated.

The width of the sheet 20 and channels 21 and 22 is such that the entire assemblage overlies the sash stops 14 at either side of the window opening a minimum of $\frac{1}{4}$ inch, sufficient to prevent the entry of flying insects therebetween while, as shown and described, the upper channel 21 overlies the upper sash stop 14 and the lower channel 22 overlies the shoulder 15, for the same purpose. The screen described thus provides adequate and effective protection against the entry of house flies, mosquitoes and other undesirable insect life. It is a full screen costing less than a framed screen large enough to protect only the bottom sash or one-half of the window. It is very easy to install and remove, roll up and store in the winter and does not require painting maintenance.

Having thus described the invention what is claimed as new and desired to be secured by Letters Patent is:

1. A window screen comprising a sheet of screen material approximating the size of the window opening to be screened, elongated clamp means secured to a margin of said sheet and adapted to be secured at the top of a window opening, top support means adjustable for plumb, level and height of window, elongated clamp means secured to the opposite margin of said sheet, cams pivoted on said second clamp means, and locking means engaging said cams and adapted to be secured at the bottom of a window opening and being adjustable for plumb, level and height of window, each said cam having a curved operative surface comprising an entering portion with a geometrically decreasing rate of rise inversely proportional to the rate of tension build-up in the screen as it is being locked, until it reaches zero rise at the locking position, the point of contact between cam and locking device, when in locking position only, being disposed directly beneath the cam pivot.

2. Window screen according to claim 1, each said cam having a handle portion extending substantially radially from said pivot, said handle portion being substantially horizontal when said locking portion of said cam surface is in engagement with said locking means, when the screen is in maximum tension and locked.

JACOB M. GWINNE.
